CLAIM

The ornamental design for an air conditioner, as shown and described.

DESCRIPTION

FIG. 1 is a front, bottom and right side perspective view of an air conditioner, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is an enlarged cross-sectional view thereof; taken along line 8—8 of FIG. 2, with the internal system omitted;

FIG. 9 is an enlarged cross-sectional view; taken along line 8—8 of FIG. 2, with the internal system omitted with the louvers opened; and,

FIG. 10 is a front, bottom and right side perspective view with the louvers opened.

The broken line disclosure in the views is understood to represent portions of the article in which the claimed design is embodied, but which form no part of the claimed design.
